UNITED STATES PATENT OFFICE.

CLAUDE RORABECK, OF NEWARK, NEW JERSEY.

GAS-PRODUCER.

1,014,522.

Specification of Letters Patent.

Patented Jan. 9, 1912.

Application filed April 29, 1911. Serial No. 624,001.

To all whom it may concern:

Be it known that I, CLAUDE RORABECK, a citizen of the United States, and a resident of the city of Newark, in the county of Essex and State of New Jersey, have invented certain new and useful Improvements in Gas- Producers; and I do hereby declare the following specification, taken in connection with the drawings forming part of the same, 10 to be a full, clear, and exact description of the principle of said invention and the best mode in which I have contemplated applying that principle, so as to distinguish it from other inventions.

15 The invention relates primarily to a gas producer in which a uniform fire is maintained by providing an arrangement to allow the fresh fuel to be fed into the decomposition zone which is above the combustion or coke zone, and of maintaining said decomposition and combustion zones in a constant state of agitation and of passing preheated steam and air through said combustion zone to form carbon dioxide, hydrogen and other 20 gases, which in turn pass through the decomposition zone to form the producer gas which consists of carbon monoxide, hydrogen and other gases.

The primary object of this invention is to 30 provide a gas producer in which the fresh fuel is injected into the burning fuel which is forming the carbon monoxide and is above the combustion zone, thereby causing the products of the destructive distillation such 35 as tar and other hydrocarbons of the fresh fuel to pass through the decomposition zone and be converted into a permanent gas.

Another feature of this invention relates to the arrangement for agitating the ash, 40 combustion and decomposition zones by means of a revolving grate, thereby preventing cavities from forming in said zones and affording a passage for undecomposed steam and air which would materially affect the 45 incandescent carbon above it.

Another feature relates to the arrangement for admitting preheated steam and air so that the same will pass through the ash and combustion zones, there to be decomposed to form carbon dioxide, hydrogen and other gases, which then pass into the decomposition zone to be formed into producer gas, which consists of carbon monoxide, hydrogen and other gases, without passing 50 through the fresh fuel which is injected into the decomposition zone.

Other features relate to the construction of the revolving grate and to the means for removing the ashes therefrom to keep the fire in the proper state, and further to a 60 means for observing the character of the fire without admitting a large volume of air and unnecessarily cooling the fire.

Still other features relate to the construction of the poke-hole plug which is so arranged that when an explosion occurs within the producer and the poke-hole plugs are blown from their seat they will immediately return to close the poke-holes without further attention and prevent the admission of 70 air into the producer.

The invention comprises a stationary furnace preferably lined with brick and having a revolving grate, arranged at its lower end, upon the center of which is a cylinder 75 mounted to rotate therewith, which is also preferably of brick, and of sufficient height to extend above the combustion zone or coke bed, said revolving cylinder being provided with a hole therethrough to allow 80 for the passage of fresh fuel into the furnace, and means arranged to pass steam and air between said revolving cylinder and the furnace walls.

The annexed drawings and description 85 thereof set forth in detail certain mechanism embodying means constituting, however, but one of the various mechanical forms in which the principles of this invention may be used.

90 The novelty of the invention will be readily understood from the drawings, which show so much of the gas producer as to properly exemplify the invention in its preferred form, and from the following description thereof.

The novelty of the invention is more particularly pointed out in the claims annexed to said specification.

In the drawings: Figure 1 is a sectional 100 view of a gas producer clearly showing the interior mechanism in its preferred form. Fig. 2 is a plan view of the revolving cylinder. Fig. 3 is a plan view of one of the sections composing the brick lining of the 105 cap of the gas producer. Fig. 4 is a plan view of one of the sectors of the revolving grate.

Referring to the drawings the base 1 is cylindrical in form, closed at the bottom and 110 provided with a circular opening through the upper wall 2. The brick furnace 3, also

2

cylindrical in form, is built upon the wall 2 of the base and is provided with a circular opening corresponding to the opening in said wall 2. A cylindrical iron jacket shell 5 4 is arranged about the brick furnace 3 and is attached at its lower end to the base 1 by means of the plate 5 and at the upper end it is attached to the producer head 6 by means of a similar plate 7.

10 In the center of the base 1 a grate stand 8 is provided having a cylindrical upward projection 9 about which the grate table 10 is arranged to rotate. The grate table 10 is provided at its lower end with a circular 15 groove between which a series of rollers 11 are inserted to form a roller bearing and carry the load. Two cylinders 12, preferably of brick, are mounted upon the grate table 10 and arranged to rotate therewith by 20 means of a hollow cylindrical table neck 13 which is secured to said grate table 10 and is provided with two keys 14 arranged diametrically opposite and engaging said brick cylinders 12.

25 The revolving grate 15 is composed of a series of sectors (see Fig. 4) inserted in the grate table 10. From the construction of this grate 15 it will be seen that the same can be readily replaced without removing 30 any fastenings, as the construction of each sector and the grate table is such that the outer end of the sector need only be raised slightly when the same can be withdrawn, while the weight of the ashes will at all 35 times keep the grate sectors in place. A bevel gear 16 is secured to the lower end of the grate table 10 and engages with and is rotated by a bevel pinion 17 secured to the grate shaft 18. A bearing 19 is provided 40 to support the grate shaft 18 at the bevel pinion end. Said grate shaft 19, which extends through the base 1, and is supported by the flange 20, may be connected with any suitable source of power to rotate the grate 45 15 and the brick cylinders 12 at a proper speed to keep the fire in constant agitation and thereby prevent any cavities from forming in the decomposition and combustion zones.

50 The grate stand 8 is provided with a curved cylindrical core 21 which passes through the cylindrical projection 9 and forms a passage for the fuel through the center of the grate 15 and corresponds with 55 the core in the cylindrical neckpiece 13. A connecting pipe 22 is provided to connect said cylindrical core 21 with a similar core 23 provided in the base 1. A fuel feed pipe 24 is secured to the base 1 and over said core 60 23 and may be connected to any suitable means for periodically supplying fuel to the furnace.

The arrangement just described provides a means to allow the fuel to be passed through the center of the grate mechanism

and up through the brick cylinders 12 into the decomposition zone above the combustion or coke zone, thereby causing the products of the destructive distillation such as tar and other hydrocarbons of the fresh fuel 70 to pass through the decomposition zone and be converted into a permanent gas.

The grate stand 8 is further provided with a cavity into which a steam pipe 25 is inserted supplying steam from any suitable 75 source. The upper part of said grate stand 8 is provided with a series of apertures through which the steam may percolate and then pass out between the rollers 11 and through the grate 15 and up through the 80 ash and combustion zone between the furnace walls 3 and the rotating cylinders 12, there to be decomposed and to form carbon dioxide, hydrogen and other gases which then pass into the decomposition zone to be formed 85 into producer gas without passing through the fresh fuel which is fed into said decomposition zone.

The preheated air, which is decomposed in a similar manner as the steam, is supplied by a pipe 26 and passes into a circular opening formed by the two vertical walls of the base 1; the inner wall being provided with a series of apertures arranged above the grate 15 to allow the preheated 95 air to pass above the ashes and through the combustion zone and then through the decomposition zone.

The ashes formed on the grate 15 are removed by means of the ash stem 27, which 100 is adjustably mounted in the base 1 and is operated by means of the hand wheel 28 and locked in any position by the hand nut 29. This arrangement provides an adjustable means to keep the fire clean without removing any of the live fuel.

The base 1 is provided with a large opening on the left end as seen in Fig. 1, through which the ashes may be removed. An ash door frame 30 is secured to said base 110 1 and over said opening and is provided with an ash pit door 31 hinged to the upper end thereof and so arranged as to automatically close by its own weight. Said ash door 31 is provided with an opening 32 therein over which a small piece of mica 33 is secured by means of a flange 34, so that the amount of ash may be observed without opening the ash pit door and admitting an unnecessary amount of cold air and thereby 115 materially affect the fire.

The gases formed in the furnace pass through the openings 35 into the head 6 and from there through the outlet pipe 36. The producer head 6 is lined at its lower end with brick 42 made up in sections as shown in Fig. 3. These sections are held in place by the T ribs 38 formed on the head 6 and by pins 37 which pass through the ends of said T ribs 38. A series of poke holes 120

39 are arranged in said head 6 and each is provided with a plug 40 guided in a vertical direction by the bearing 41 which is secured to the head 6. Said bearing 41 is arranged 5 as a stop for said plug 40 when the same is blown out due to an explosion in the producer. The vertical guide for the plug 40 further insures the return of said plug 40 to close the poke hole 39, thereby preventing 10 cold air from being admitted into the producer.

The operation of the producer is as follows: A fire having been started in the producer the fuel is injected into the decomposition zone above the combustion or coke zone through the center of the revolving grate and brick cylinder by any suitable 15 stoker attached to the pipe 24. By feeding the fresh fuel into the decomposition zone 20 as described, the products of the destructive distillation of the fresh fuel such as tar and other hydrocarbons are caused to pass through the decomposition zone there to be absorbed, and thereby producing a gas free 25 from these volatile constituents. The fire is kept in constant agitation by revolving the grate and the brick cylinders by means 30 of any suitable mechanism attached to the shaft 18, thereby preventing the formation of cavities in the fire through which any undecomposed air and steam may pass. The ashes are constantly removed from the revolving grate by properly adjusting the 35 grate as it is found necessary when observing the fire through the mica in the ash door. The preheated steam and air pass through the ashes and the combustion zone to form 40 carbon dioxide, hydrogen and other gases which then pass through the decomposition zone to form the producer gas, without passing 45 through the fresh fuel, which is fed into the decomposition zone through the center of the revolving brick cylinder, and thereby enables said preheated steam and air to be properly decomposed. The gases as they 50 are formed are then taken off at the upper end of the cylinder in any suitable manner.

Having described my invention and its mode of operation, I claim and desire to secure by Letters Patent:

1. The combination with a furnace, of a revoluble grate therefor, a cylinder mounted upon said grate and rotatable therewith and arranged to project above the combustion zone of the fire, and an opening through 55 said grate and cylinder to form a passage for the fresh fuel into said furnace above the combustion zone of the fire.

2. The combination with a furnace, of a base therefor, a fuel feed pipe connected to said base, a grate stand mounted in said base, a revoluble grate mounted upon said grate stand, a cylinder mounted upon said grate and rotatable therewith and arranged to project above the combustion zone 60 of the fire, and an opening through said cylinder, grate and grate stand, and connected with said fuel feed pipe to form a passage for the fresh fuel into the decomposition zone of the fire in said furnace. 65

3. The combination with a furnace, of a base therefor, a fuel feed pipe connected to said base, a grate stand mounted in said base, a revoluble grate mounted upon said stand, a cylinder mounted upon said grate and rotatable therewith and projecting above the combustion zone of the fire, an opening in said cylinder, grate and stand connected with said fuel feed pipe to form a passage for the fresh fuel into the decomposition zone of 70 the fire in said furnace, and means operable from without said base to rotate said grate and cylinder. 75

4. The combination with a furnace, of a base therefor, a revoluble grate, a cylinder 85 mounted upon said grate and projecting above the combustion zone of the fire in said furnace, a fuel feed pipe connected to said base, and connections from said pipe to said furnace whereby the fresh fuel may 90 be fed into the decomposition zone of the fire.

5. The combination with a furnace, of a base therefor, a fuel feed pipe connected to said base, a revoluble grate, a cylinder 95 mounted upon said grate and arranged to project above the combustion zone of the fire, an opening through said grate and cylinder, and connections from said opening to said feed pipe to form a passage for the fresh fuel into the decomposition zone of 100 the fire.

6. The combination with a furnace, of a revoluble grate therefor, a cylinder mounted upon said grate and rotatable therewith, 105 and constructed to extend a considerable height within the producer structure and above said grate, and an opening through said grate and cylinder to form a passage for the fresh fuel into said furnace above 110 the combustion zone of the fire.

CLAUDE RORABECK.
